UNITED STATES PATENT OFFICE.

FRANZ BURGER AND HENRY M. WILLIAMS, OF FORT WAYNE, INDIANA;
SAID BURGER ASSIGNOR OF ONE-HALF OF HIS ENTIRE RIGHT TO SAID
WILLIAMS.

RECEIVER AND REHEATER FOR COMPOUND ENGINES.

SPECIFICATION forming part of Letters Patent No. 790,284, dated May 23, 1905.

Application filed May 26, 1900. Serial No. 18,116.

To all whom it may concern:

Be it known that we, FRANZ BURGER and HENRY M. WILLIAMS, citizens of the United States, residing at Fort Wayne, in the county 5 of Allen and State of Indiana, have invented certain new and useful Improvements in Receivers and Reheaters for Compound Engines, of which the following is a specification.

Our invention relates to compound engines, 10 and more especially to those for use in locomotives; and our invention consists in constructing such engines, as fully set forth hereinafter, so as to prevent the cooling of the exhaust between the high-pressure and low- 15 pressure cylinders.

In the accompanying drawings, Figure 1 is a transverse sectional elevation through the cylinders, boiler, and intermediate chamber; Fig. 2, a sectional view through the parts 20 shown in Fig. 1 on the line *b*; Fig. 3, a sectional view on the line *a*.

A represents the boiler, B the high-pressure cylinder, and G the low-pressure cylinder, of a locomotive-engine, the cylinder B 25 having a valve-casing B' and the cylinder G a valve-casing G', with any suitable arrangement of inlet and outlet ports, so that the low-pressure cylinder may receive the exhaust-steam from the high-pressure cylinder.

C is a superheater of any suitable character. 30 As shown, it is a steam-coil arranged in the combustion-chamber 3, so as to be subjected to the products of combustion until they have passed through the tubes of the boiler whereby to highly heat the steam passing through the same, so that it shall enter the high-pressure cylinder in a much more highly superheated condition than with the usual construction. The superheating-coil, however, does

40 not extend directly to the high-pressure cylinder, but connects with a coil 4 in a chamber 5 within what we term a "receiver" D, the same being a casing united with the cylinders and formed into a saddle for the boiler.

45 A. The coil 4 communicates with the throttle-valve casing 10, and the throttle-valve casing also communicates with the valve-casing B', so that the steam from the coil 4 may pass from the throttle-valve casing to the inlet-

ports of the high-pressure cylinder. The outlet-port *x* of the high-pressure cylinder communicates with a passage leading to a nozzle 7, which conducts the exhaust-steam from the high-pressure cylinder into the chamber 5 of the receiver, so that the said exhaust-steam 55 will have its heat maintained to a very great extent by the coil 4. The chamber 5 communicates through a port *y* (shown in dotted lines, Fig. 1) with the valve-casing G', from which the exhaust-steam from the chamber 5 60 can pass through the inlet-port of the low-pressure cylinder G. By thus passing the exhaust-steam from the high-pressure cylinder over a heater and reheating the same it is caused to enter the low-pressure cylinder at a 65 much higher temperature than would otherwise be the case and can be used with better expansive effect, and this result is further increased by using highly-superheated steam in the first instance for supplying the high-pressure cylinder, as the exhaust from the high-pressure cylinder in such case passes to the low-pressure cylinder at a higher temperature than that of the live steam in the high-pressure cylinder in apparatus of the ordinary 75 construction.

It is sometimes desirable to direct the exhaust-steam from the high-pressure cylinder directly to the exhaust without passing it to the low-pressure cylinder, and we therefore 80 provide the high-pressure cylinder with an exhaust-passage *w*, communicating with an independent channel *v*, leading to the exhaust pipe or nozzle 12 in the combustion-chamber of the boiler. Any suitable means may be 85 provided whereby the exhaust may be directed from the port *x* to the channel *w*.

The exhaust-port *u* of the low-pressure cylinder G communicates with the channel *v*, leading to the nozzle 12. 90

Without limiting ourselves to the precise construction and arrangement of parts shown, we claim—

1. The combination with the boiler and the high and the low pressure cylinders of a locomotive-engine, of a chamber arranged between said cylinders below the boiler and adapted to conduct the exhaust-steam from the high

to the low pressure cylinder, a coil within said chamber communicating with the high-pressure cylinder, and a superheater communicating with said coil, substantially as described.

- 5 2. The combination with the boiler and the high and the low pressure cylinders of a locomotive-engine, of a chamber arranged between said cylinders below the boiler and communicating with the low-pressure cylinder, a coil
10 within said chamber communicating with the high-pressure cylinder, and a superheater lo-

cated in the combustion-chamber of the boiler and communicating with said coil, substantially as described.

In testimony whereof we have signed our 15 names to this specification in the presence of two subscribing witnesses.

FRANZ BURGER.

HENRY M. WILLIAMS.
